(57) **CLAIM**

The ornamental design for a hinged flange for a jet boat pump, as shown and described.

DESCRIPTION

FIG. 1 is a perspective view of a hinged flange for a jet boat pump in an open position;

FIG. 2 is perspective view of the hinged flange for a jet boat pump in a closed position;

FIG. 3 is an exploded view of the hinged flange for a jet boat pump. The broken lines in FIG. 3 illustrate the position of the exploded parts of the hinged flange for a jet boat pump and form no part of the claimed design.

FIG. 4 is a front view of the hinged flange for a jet boat pump;

FIG. 5 is a rear view of the hinged flange for a jet boat pump;

FIG. 6 is a top view of the hinged flange for a jet boat pump;

FIG. 7 is a bottom view of the hinged flange for a jet boat pump;

FIG. 8 is a right side view of the hinged flange for a jet boat pump; and,

FIG. 9 is a left view of the hinged flange for a jet boat pump.
